2 SHEETS—SHEET 2.

By Abraham Edger his Attorney

UNITED STATES PATENT OFFICE.

DAVID J. GAMPP, OF KANE, PENNSYLVANIA.

AWNNG-BLIND.

1,251,499.

Specification of Letters Patent.

Patented Jan. 1, 1918.

Application filed April 8, 1915. Serial No. 19,886.

To all whom it may concern:

Be it known that I, DAVID J. GAMPP, a citizen of the United States, residing at Kane, in the county of McKean and State of Pennsylvania, have invented certain new and useful Improvements in Awning-Blinds, of which the following is a specification.

This invention relates to improvements in suitable screens to be used either as awnings or blinds for windows, doors or other openings in buildings.

The main object of the invention is to provide a structure which can be placed at any desired position as an awning and also in the usual position as a blind by the same operative means.

A further object of this invention is to provide a structure that can be folded to compact form against the building or support when not in use, and at the same time adapted to shed water effectively when placed in position to be used either as an awning or as a blind.

A further object of this invention is to provide convenient means of operation, by which the structure can be placed in the several desired positions from that of a vertical position as a blind, to that of a folded position, by the same operative means.

A further object of this invention is to provide a structure which can be made of either wood and metal, or wholly of metal, and when constructed of metal may be adapted to be used as a fire proof shutter or as a fire door.

With the foregoing and other objects in view, which will appear as the description proceeds, my invention resides in the combination and arrangement of parts, and in the details of construction hereinafter described and claimed. It being understood that changes in the precise embodiment of the invention herein disclosed can be made within the scope of what is claimed without departing from the spirit of the invention.

In order that my invention may be fully understood, attention is hereby directed to the accompanying drawings forming a part of this specification, and in which,

Figure 1 is an inner face view of the invention, illustrating it as closing the entire window.

Fig. 2 is a side elevation showing same in closed position as a blind.

Fig. 3 is a side elevation showing device folded at the top of the window.

Fig. 4 is a side elevation showing the device in position as an awning.

Fig. 5 is an enlarged side elevation of the slat members with locking means. 60

Fig. 6 is an enlarged perspective view of one of the slat joining members.

In the drawings I have shown my invention in the preferred form applied to the ordinary window of a building, but it is 65 to be understood that there are other uses for my invention, and the precise form herein shown need not be followed in every instance, the structure to which I have shown my invention applied, consists of a 70 window casing 1, consisting of the side frames 2 and 3, and the upper and lower sills 4 and 5.

As shown, the awning structure proper consists of a plurality of planes 6, mounted 75 in such way that they will turn axially upon their support. For this purpose I have provided the bars or levers 12, in pairs to which the ends of the planes are secured in any suitable manner, I prefer to secure them 80 however in the manner shown by flattening that portion of the lever 12, which comes in contact with the planes 6 and by suitable rivets or otherwise securely attaching the planes thereto. 85

I prefer to make these levers of heavy wire whereby their ends 11, may be bent outwardly toward the window casing sides 2 and 3, and to register with and be pocketed in the holes 10, so that the levers may rotate 90 axially therein.

By making the levers 12 of increasing length for each of the planes, from the upper to the lower plane, I provide a novel arrangement of housing or folding the awning structure in a compact position against the upper part of the casing sill 4. 95

In the uppermost plane 6^A the supports are in the form of a dowel pin, and in the next lower plane, the supports are of the 100 design as above indicated, comprising a pair of levers 12, and for each succeeding downwardly positioned plane the pair of levers 12 are of a progressively increasing length, and the levers of the lowest plane 6^H, being 105 greater than the rest. The purpose of the gradual increase in the length of the levers 12, is to cause or permit the planes to overlap when the awning is folded, so that the second plane from the top 6^A will overlap 110 the top one 8, the third plane 6^B will overlap the first and second, etc., and the lower

most plane 6^H will therefore be arranged with bars of suitable length to permit it to overlap all of the planes above it.

To raise the blind, or to adapt it to be suspended as an awning, as shown in Fig. 4, I provide a flexible metallic belt 13, adapted to be at the one end, securely attached at the edge of the lowermost plane 6^H, and to extend upwardly passing through the aperture 14 in the stationary panel 8 at the top of the window and thence to be made fast to a roller 15, suitably suspended in journaled brackets 16-16' for rotative movement. As the roller 15 is rotated the belt 13 is wound thereon in the guiding race 17 by which operation, the lowermost panel 6^H is moved from the position shown in Fig. 2, to that position shown in Fig. 4, when it is desired to place the structure in position as an awning. By continuing the rotation of the roller 15 the outermost panel 6^H will be moved to the position shown in Fig. 3, showing the structure in a folded position.

For the purposes of facilitating the rotative movement of the roller 15, I provide for placing on one end thereof a sprocket wheel 18, and on the lower sill 5 of the window a suitable bracket 19, having a horizontally extended spindle 20. Mounted on the spindle 20 and adapted for rotative movement, I mount a sprocket wheel 21, and connecting the sprocket wheels 18 and 21 is a sprocket chain 22, mounted on the sprocket wheel 21 and adapted to give rotative movement thereto is a crank 23. For the purposes of maintaining the roller 15 in any fixed rotative position I provide the pawls 24 adapted to engage any given link of the chain 22, for the purpose of holding it in a stationary position.

I have provided means for retaining the several planes in spaced relation when the awning is down, and adapted to constitute a blind and for this purpose, I provide a novel device comprising the clip 7 shown in Fig. 6.

When the planes 6 are composed of wood, I prefer to make the clip 7, of brass or other non-corrosive metal and as shown in Fig. 6, it is formed with a vertical face 25, having suitable rivet or screw holes 26 for attaching it to the wooden slat forming the plane 6. Extending outwardly in a horizontal position at the bottom of the face 25 is a projecting ledge 27 having an upturned flange 28 the distance between the flange 28 and the vertical face 25 is substantially that of the thickness of the panel forming the plane 6. Extending outwardly from the upper edge of the face 25 is a horizontally disposed flange 29. Projecting downwardly from the flange 29 is a tongue 30. Located within the vertical face 25 of the clip 7, is a U shaped slot 31 which forms the tongue shaped member 32. Located in the lower

projecting ledge 27 is a rectangular aperture 33 diagrammatically shown in Fig. 6.

In the adaptation of the clip 7, in its operative form, the tongue 32 is depressed in a pocket formed in the slat comprising the plane 6, in such manner that, that portion of the lower edge of the vertical face 25 below the U shaped slot, and extending to the rectangular aperture 33, will form a horizontal bar or stirrup 34, with which the tongue 30 of the lower contiguous plane will register and be supported when the planes 6 are in the relative position shown in Figs. 1, 2, and 5, wherein the structure is shown used as a blind.

By the novel construction of the clip 7, I provide locking means for retaining the several planes in spaced relation when the structure is used as a blind, and which will also permit the same to automatically disengage the locking means when the structure is being elevated toward the position of being folded.

When the structure is comprised wholly of metal, the locking and spacing features provided for by the clip 7, may be formed integral with the metal panel, that is, I may dispense with the separate member comprising the clip 7, and I may form within the panel 6, the supporting stirrup 34, and also provide for the tongue 30, to be formed from an extension from the upper edge of the panel, in fixed relative position to register with the stirrup 34 of the next upper panel.

When the structure is being elevated to be folded above the window as shown in Fig. 3, as the lower most plane 6^H moves in an upward and outward position describing an arc, the contiguous upper plane will likewise move in the path of an arc, and will have an outward sliding movement across the face of the lowermost plane, thus disengaging the tongue 30 of the lower plane from the stirrup 34 of the upper contiguous plane. The same operation of disengaging the tongue 30 from the respective stirrup 34 of the contiguous planes will be in process of operation throughout the various contiguous planes.

To provide for effectively locking the blind in a closed position, I attach to the inside face of the lower panel 6^H, a spring actuated locking pawl 35, adapted for locking engagement with the member 36, securely fastened to the lower sill 5. The spring 37 yieldingly holds the pawl in locked position, and is adapted to be automatically compressed as the pawl 35, rides upward on the member 36, in the closing operation of the movement of the lower panel 6^H.

To provide a housing to extend over the assembled panels when folded in the position shown in Fig. 3, I provide for extending outwardly from the upper sill 4, having a slightly downward deflection, a cover 130

member 38. Attached to the cover member 38 are vertically disposed brackets 39, attached to the cover by suitable hinges 40, providing means whereby the brackets 39 may be folded in a horizontal position above the several assembled panels as shown. When the structure is in the position shown in Figs. 1, 2 and 4, the brackets 39 are placed in a vertical position and when so placed add to the appearances of the housing comprising the cover member 38 as well as affording a shield against the possibility of rain beating in against the top panel 8, and finding its way between the contiguous edges of the panel 8 and the panel 6^H.

In constructing my apparatus wholly of metal, or of fire resisting material, I may adapt the same to be used as a fire proof shutter or for closing necessary openings in fire resisting bulkheads, commonly placed in walls between manufacturing plants and their store houses, or other adjacent buildings which may contain more or less inflammatory material, and when so placed may be adapted to form a roof or storm cover, over the walkway between the factory and store room, for the protection of workmen in going to and from the store house.

When my apparatus is to be used as means for fire protection, I may provide for connecting its operative means for lowering the same, in any suitable way, with any of the automatic devices well known in the art, for closing fire doors, operative through the application of a given degree of heat to a rheostat or other forms of heat operated mediums.

The operation is as follows: Assuming that the structure is in the position shown in Figs. 1 and 2, and serving as a blind for closing in the entire window, and it is desired to open the same, the pawl 35 is moved to disengage itself from the keeper 36, which allows the panel 6^H, to move outward and to swing in a vertical plane on the pair of supporting levers 12. The crank 23, is rotated which, through the sprocket 21, operating the sprocket chain 22, connecting the sprocket wheel 18, rotates the roller 15. As the roller 15 is rotated so as to wind the flexible member 13, thereon, the pull on this flexible member, will cause the lower panel 6^H, to swing outwardly and upwardly causing the other panel members to fold on one another as shown in Fig. 4. When the desired elevation of the lower panel 6^H, has been reached, to properly shade the sunlight from the window, the engaging dog 24, is placed in contact to register with the proper link of the sprocket chain 22, and to thereby hold the awning in the position desired.

When it is desired to fully elevate the structure above the window, the roller 15 is further rotated, until the flexible member 13 has been wound thereon to such an extent as

to draw the panel 6^H, from the position shown in Fig. 4, to that position shown in Fig. 3.

In the operation of elevating the structure from the position shown in Fig. 2, to the position shown in Fig. 4, it will be observed that there will be a forward sliding movement of each panel over the next lower supporting panel, which will cause a disengagement of the tongue 30, projecting from the lower panel, from that of the connecting bar or stirrup 34, of the next contiguous upper panel. This disengaging movement will be gradual, and will be consummated at or about the time, when each pair of contiguous panels have assumed substantially the horizontal position, and while the members 30 and 34 have become disengaged, the various panels will be supported in their outwardly extended position by resting upon the next lower panel, and the lowermost panel 6^H will have for its supporting means, the flexible member 13.

With a continuation of the rotative movement of the roller 15, the flexible member 13 will continue the rotative movement of the panel 6^H, until all of the overlapping panels have had their respective locking means disengaged and the panels have been folded one upon the other, in the position shown in Fig. 3.

When it is desired to again lower the structure, obviously rotating the roller 15, in an inverse direction, will allow each panel to swing outwardly from the position shown in Fig. 3, and in such outward movement, the lower panels will slide outwardly on each upper panel in such manner that the tongue 30 on the lower panel will lockingly engage the stirrup 34, on the next upper or contiguous panel, thereby automatically connecting the panels as the structure has gradually been moved to the position shown in Figs. 1 and 2.

It will be obvious that many changes may be made in the arrangement of, and the construction of the various parts without departing from the spirit and scope of my invention.

Having thus described my invention what I claim and desire to secure by Letters Patent is:

1. An awning comprising a plurality of panels, a pair of supporting elements for each panel pivotally mounted for oscillating movement in a vertical plane, means for actuating the oscillation of the supporting means to elevate the panels comprising a flexible member connected to the lowermost panel, whereby all the panels may be elevated through a vertical plane by the application of draft to said flexible member.

2. An awning comprising a series of slats each pivoted about an axis above the slat, the axes of said slats lying consecutively

substantially in a plane, the distances between the slats and their axes progressively increasing from top to bottom, whereby the slats when in lowered position lie consecutively in a plane and when swung upwardly about their axes, they terminate in a folded position, wherein the lower edge of each panel will lie in a plane common to all.

3. An awning comprising a series of slats each pivoted about an axis above the slat, the axes of said slats lying consecutively substantially in a plane, the distances between the slats and their axes progressively increasing from top to bottom whereby the

slats when in lowered position lie consecutively in a plane and when swung upwardly about their axes, they terminate in a folded position, wherein the lower edge of each panel will lie in a plane common to all, with means for interlocking the contiguous edges of the panels, becoming operative as the panels assume their unfolded position.

In testimony whereof I have affixed my signature in presence of two witnesses.

DAVID J. GAMPP.
